UNITED STATES PATENT OFFICE.

JOSEPH L. HARRINGTON AND JOSEPH J. SCHERMACK, OF CHICAGO, ILLINOIS, ASSIGNORS TO THEXTON ELECTRIC ENVELOPE SEALER CO., OF CHICAGO, ILLINOIS, A CORPORATION OF ILLINOIS.

ENVELOP-SEALING MACHINE.

SPECIFICATION forming part of Letters Patent No. 758,359, dated April 26, 1904.

Application filed December 29, 1903. Serial No. 187,010. (No model.)

To all whom it may concern:

Be it known that we, JOSEPH L. HARRINGTON and JOSEPH J. SCHERMACK, citizens of the United States, residing at Chicago, in the county of Cook and State of Illinois, have invented a certain new and useful Improvement in Envelop-Sealing Machines, of which the following is a full, clear, concise, and exact description, reference being had to the accompanying drawings, forming a part of this specification.

Our invention relates to machines for automatically sealing envelopes.

Prominent objects of the invention are to provide a simple, practical, and inexpensive machine of this kind, to arrange for the effective sealing of the envelopes, to secure this result irrespective of the size of the inclosure therein, to arrange for the easy and ready feeding of the envelopes, and especially to provide a machine which can be manually operated and can be constructed at such a low expense as to make it available in comparatively small houses or establishments which would not be justified in purchasing an expensive machine of this kind.

In the accompanying drawings, Figure 1 is a front elevation of an envelop-sealing machine embodying our invention. Fig. 2 is a cross-section taken on line 22 in Fig. 1. Fig. 3 is a plan view of the machine with certain parts removed for convenience of illustration. Fig. 4 is a section taken on lines 44 in Figs. 3 and 5. Fig. 5 is a section taken on line 55 in Fig. 4.

The machine is provided with a body-frame A, consisting, essentially, of a horizontal platform 1, provided with legs 22. The platform 1 is constructed with a back wall 3 at its left-hand portion and depending or overhanging portions 44 at its right-hand end, Figs. 1 and 2, and it is provided with an opening or aperture 5 near said right-hand end, as shown in Fig. 3.

A hood 6 is fixedly secured to a platform 1, the hood 6 having a portion 7 fitting against and secured to the back overhang 4, as well shown in Fig. 2. A pair of feed-rolls 8 and 9 are provided, the upper roll 9 being ar-

ranged in and at the left-hand end of the hood 6 and the lower roll 8 being below the roll 9 and at the left-hand end of the aperture 5 in the platform 1. The lower roll 8 is mounted on the shaft 10, journaled in the overhangs 44 of the platform 1. The upper roll 9 is mounted on a shaft 11, which is carried by journal-boxes 1212. These boxes 1212 work in guideways formed by vertical guides 1313, provided on the hood 6, and they are suspended by springs 1414, which are supported by and subject to adjusting-screws 1515, passing through the top of the hood 6. A pair of sealing-rolls 1617 is arranged to the right of the feed-rolls 8 and 9, the upper sealing-roll 16 being arranged in and at the right-hand end of the hood 6 and the lower roll 17 being below the roll 16 and in the right-hand end of the aperture 5 in the platform 1. The sealing-rolls 16 and 17 are mounted in a manner similar to the mounting of the feed-rolls 8 and 9, the roll 17 being carried by a spindle 18, journaled in the overhangs 44, and the upper roll 16 being mounted in spring-suspended boxes controlled by screws 19. A handle 20 is secured to one end of the shaft 18, and this shaft and the shaft 10 for the lower feed-roll 8 are geared together by means of a sprocket-chain 21, traveling over sprocket-wheels on said shafts. It will be seen on referring especially to Figs. 2 and 3 that the feed-rolls 8 and 9 are comparatively narrow and are arranged at the forward—that is, the near—ends of the shafts 10 and 11, whereas the sealing-rolls 16 and 17 are materially wider and are mounted at the rear or far ends of their shafts.

A flap depressor or closer 22 is arranged in the hood 6 between the feeding and sealing rolls, as best shown in Figs. 1 and 3. This device consists of an inclined and curved blade 90 having a downward extension or flange 23. It is mounted by being pivotally supported at its forward end by a pivot 24, attached to a bracket 25 on the hood 6. A plate 27 is arranged over the rear portion of the platform 1, the platform being slightly cut away, beginning at the line 28, to permit the plate 27 to be flush with the upper surface of the plat-

form. This plate 27 is cut away at 29 to allow room for the lower feed-roll 8 and has a tail portion 30, which extends backwardly to substantially the lower sealing-roll 17. This 5 tail portion 30, which is substantially below the flap-closer 22, is somewhat bent, as shown in Fig. 1, and is somewhat elastic or springy.

A moistening device B is arranged slightly above the platform 1 at a point between the 10 rear upright wall 3 of said platform and the hood or housing 6. This moistening device B consists, essentially, of a composite structure or box embracing a top piece 31, a bottom 33, and a wick-retainer 32. The top piece 31 is in 15 the nature of a flat plate having vertically-disposed ribs 34 34, between which are located apertures 33 35, and having at one end an overhang 36 and at the other an inclined tailpiece 38. The top 31 also has a downwardly-projecting longitudinally-extending rib 37, which terminates in the tailpiece 38. One side of the top 31 is constructed with a lip 31^a, Figs. 1 and 3. The wick - retaining piece 32 is constructed with three substantially parallel 20 prongs 39, 40, and 41, terminating in a flat lateral flange 42. The bottom piece 33 is constructed with a body portion having two upwardly-projecting longitudinally-extending ribs 43 43, terminating in a flange 44, which 25 is adapted to fit against the inner face of the front overhang 36 of the top 31. The moistening device thus constructed is provided with a wick 45, which is arranged with an end portion 46 between the wick-retainer 32 and bottom 33 in such a manner that the prongs 39, 30 40, and 41 of the piece 32, fitting as they do between the ribs 43 43 of the bottom 33, cause the wick to assume an undulating appearance or shape, as shown in Fig. 5. The rib 37 on the 35 piece 31 extends down into the space between the two undulations of the wick, as shown in said figure, and a small space remains between the top of said piece 31 and the upper surface of the wick. This space is open at both sides, 40 (referring to Fig. 5,) and an inclined surface 33^a on the bottom 33 forms an inclined approach to it. From between the retainer 32 and bottom 33 the wick extends upwardly, as 45 shown in Fig. 4, between the flange 42 and the overhang 36 and thence backwardly over the 50 upper surface of the top 31, as shown in Figs. 4 and 5, and thence downwardly outside of the tailpiece 38. The moistening device is secured in position by a screw 47 passing through the 55 tailpiece 38 and into the back overhang 4 of the platform 1. Screws 48 and 49 pass through the overhang 36 of the top 31 and engage the flange 42 of the bottom 33, acting to hold the latter in position. The screw 48 is a thumb- 60 screw and can be unscrewed so as to be disengaged from the bottom 33. The screw 49 is adapted to serve as a pivot, so as to permit the bottom 33 to swing downwardly when released from the screw 48. The retainer 32 is fitted 65 or wedged between the top 31 and the bottom

33, the flange 42 coming into position with its upper edge against the lower side of the top 31, as well shown in Fig. 5. The retainer is thus held in position by the engagement of its prongs with the wick 45, and the latter is in 70 turn held in position by the retainer.

A tank or reservoir 50 is arranged above the moistening device B, being conveniently supported upon an arm or bracket 51, secured to the hood 6. This tank 50 has a faucet or 75 outlet 52, located above that portion of the wick 45 which extends across the top of the moistening device. A second tank or reservoir 53 is arranged below the moistening device B, being conveniently supported by a 80 downwardly-extending bracket 54, conveniently made integral with the platform 1. These two tanks or reservoirs 50 and 53 are supplied with the liquid, usually water, which is to moisten the wick of the moistening device, and this wick is extended downwardly 85 from the moistening device into the lower tank 53, as shown in Figs. 1 and 2, where its lower portion is immersed.

An adjustable guide 55 is arranged upon the 90 left-hand portion of the plate 27, as shown in Figs. 1 and 3. This guide has a curved edge 56 and a slotted arm 57, the slot of which receives a screw 58, which passes through a shelf or bracket 59, secured to the platform 1, so 95 as to hold said guide in position.

The operation of the machine is as follows: The envelopes containing the inclosures and ready to be sealed are placed upon the platform 1, conveniently arranged in a pile at the left-hand end thereof. The stop-cock 52 of the tank 50 is turned so as to allow liquid to drip slowly from the tank onto the exposed portion of the wick of the moistening device. The guide 55 is adjusted to accommodate the width of envelopes 100 to be sealed. The handle 20 is then rotated continuously by the right hand, and the envelopes are fed one by one by the left hand along the platform 1 and into the machine, the operator standing in front of and facing the machine 105 as it appears in Fig. 1. As each envelop passes along its flap enters the moistening device B and its front end is engaged by the feed-rolls 8 and 9, so that the latter continue to advance the envelop as they revolve. The flap passes 110 through the space under the top 31 of the moistening device and above the undulating portion of the wick 45, as shown in Fig. 5, the flap being of course slightly bent in passing between the undulations of the wick and below the rib 37. The lower or gummed portion of the flap thereby comes in contact with the wick of the moistening device and becomes moistened, the bending to which the flap is subjected insuring a firm and thorough 115 contact with the wick and a consequent thorough moistening of the gum. As the flap leaves the moistening device it passes under the lip 31^a thereof and is bent partially down. 120 As it continues its movement it passes under 125 the overhang 36 and is held in position by the screw 49. The flap then passes under the tailpiece 38 and is held in position by the screw 47. As it continues its movement it passes under 130

the flap-closer 22, which gradually but effect-
ively bends or pushes it downwardly toward
the body of the envelop, the latter at this
time passing along the tailpiece 30 of the plate

5 27. The envelop with its flap substantially
closed then passes between the sealing-rolls
16 and 17, where it is effectually sealed.

The liquid constantly dripping on the moisten-
ing device keeps the wick properly moist
10 for the sealing of the envelopes one after an-
other. If too much liquid should drip onto
the moistening device, it will run down the
wick and into the reservoir 53. The presence
15 of liquid in this latter reservoir and the im-
mersion of the lower end of the wick therein
also helps to keep the wick evenly moist.
When it is desired to adjust or rearrange or
replace the wick of the moistening device, the
20 latter is opened either by unscrewing the screw
48 and swinging the bottom 33 down about
the screw 49 as a pivot or by unscrewing both
the screws 48 and 49 and removing the re-
tainer 32 and bottom 33 bodily. The moisten-
25 ing device can be bodily removed, if wished,
by removing the screw 47.

It will be seen that the machine thus de-
scribed has many advantages, among which
may be mentioned the following:

First, extreme simplicity, with the result
30 that it is very inexpensive to construct and
maintain.

Second, effective, thorough, and proper
moistening of the gum on the envelop-flap.
This is due to the construction of the moisten-
35 ing device by which the flap is pressed
against the wick and then partially closed and
by which also the portion of the wick against
which the flap presses is kept uniformly moist
and prevented from becoming unduly wet.
40 The surplus liquid, if any, accumulates, run-
ning off the top of the wick into the reservoir
53 and the wick extending down into the lower
reservoir and being partially immersed there-
in serving to keep the wick always moist.

45 Third, accommodation of envelopes varying
greatly in thicknesses because of different-
sized inclosures. This is due largely to the
construction and arrangement of the flap-
closer 22 in connection with the slightly-yield-
ing bed provided by the tailpiece 30.

Fourth, the machine can be operated by
hand, thus saving the cost of mechanical or
electrical power, and at the same time great
55 speed can be secured, as envelopes can be fed
in very rapid succession along the platform 1
by the left hand while the handle is being
turned by the right hand.

It will be understood that although this ma-
chine is shown as a manually-operated ma-
60 chine the various features of improvement
can be embodied in a power-driven machine
as well. We do not, therefore, wish to confine
ourselves, so far as the principles of construc-
tion and operation are concerned, to a manu-
65 ally-driven machine; nor do we wish to be un-

derstood as confining ourselves to the precise
arrangement herein set forth, as changes and
modifications can obviously be made without
departing from the spirit of the invention.

What we claim is—

70 1. In an envelop-sealer, a moistening device
having a wick, and an independent tank or res-
ervoir mounted above the level of the wick and
provided with means for permitting the liquid
to drop on said wick, substantially as described. 75

2. In a device of the class specified, the com-
bination of a tank or reservoir, a moistening
device having a wick adapted to receive liquid
from said tank or reservoir, and a second tank
or reservoir located substantially below the 80
moistening device, the wick from the latter
being extended down to said second-mentioned
tank or reservoir, substantially as described.

3. In a device of the class specified, a moisten-
ing device having separated and elevated 85
moistening-surfaces, and means for pressing
the article to be moistened into the space be-
tween said surfaces, substantially as described.

4. In a device of the class specified, a moisten-
ing device whose moistening-pad has an un- 90
dulating or irregular surface and an abutment
projecting into the space between the undula-
tions or irregularities of said surface, sub-
stantially as described.

5. In a device of the class specified, a moisten- 95
ing device having a moistening-pad, said
moistening device being provided with means
for depressing the surface of the moistening-
pad at intervals, and being also constructed
with an abutment projecting into said depres- 100
sion in said pad, substantially as described.

6. In a device of the class specified, a moisten- 105
ing device comprising a moistening-pad,
means for holding the same and engaging the
edges thereof, means for holding a portion of
the pad between its edges in a depressed po-
sition, means for supporting the intermediate 110
portions of the pad in an elevated position,
and a cover or top having a rib projecting into
the space between said elevated portions, sub-
stantially as described.

7. In a device of the class specified, a moisten- 115
ing device comprising a bottom having ele-
vated ribs at intervals from one another, a
retainer having longitudinally-extending
prongs arranged lengthwise of said ribs, one
of said prongs being between said ribs and the
others outside thereof, a wick engaged by the
ribs on the bottom and also by said prongs so
that the outer edges of the wick are held de- 120
pressed by the outer prongs and the middle
portion of the wick is held depressed by the
middle prong, the intermediate portions of
the wick being held in an elevated position by
said ribs, and a cover having a rib arranged 125
lengthwise of and above said middle prong,
whereby it projects into the space between the
elevated portions of the wick, substantially as
described.

8. In a device of the class specified, a moisten- 130

tening device comprising a bottom or base piece 33 having longitudinally-extending ribs 43, 43, a wick-retainer 32 having prongs 39, 40 and 41, a top 31 having a depending rib or projection 37, and means for detachably holding the said parts together, substantially as described.

9. In a device of the class specified, a moistening device comprising a base or bottom 33 having ribs 43, 43, a wick-retainer 32 having prongs 39, 40 and 41, a wick 45 engaged by the prongs of said retainer 32, a top piece 31 having a rib 37 above the central prong 40, and screws 48 and 49 for detachably holding the pieces 33 and 31 together, the retainer 32 being provided with a flange 42 whereby its prongs are held in engagement with the wick, substantially as described.

10. In a device of the class specified, a moistening device having a moistening-pad and an abutment arranged opposite the same for pressing the article to be moistened against the pad, said pad having an exposed extension, and a tank or reservoir mounted above the level of said extension and adapted to supply the same with liquid, substantially as described.

11. In a device of the class specified, a moistening device comprising bottom and top pieces, a moistening-pad arranged between the same, and an extension of said pad above said top piece, substantially as described.

12. In a device of the class specified, a moistening device comprising bottom and top pieces, a moistening-pad arranged between the same, an extension of said pad above said top piece, and means for supplying said extension with liquid, substantially as described.

13. In a device of the class specified, a moistening device comprising a moistening-box containing a wick, said box having side apertures through which the article to be moistened can pass and also having its top provided with apertures, and an extension of said wick arranged across the top, substantially as described.

14. In a device of the class specified, a moistening device comprising a moistening-box containing a wick, said box having side apertures through which the article to be moistened can pass and also having its top provided with apertures, an extension of said wick arranged across the top, and a tank or reservoir arranged to supply liquid to said wick extension, substantially as described.

15. In a device of the class specified, a moistening device comprising a box having openings through which the article to be moistened can pass, a wick arranged within said box, said wick having an undulating or irregular surface and the top of the box being provided with a projection extending into the space between the undulations or irregularities of the wick, an extension for said wick 65 extended across the top of the box, and a

tank or reservoir arranged to supply liquid to said extension, substantially as described.

16. In a device of the class specified, the combination of a moistening device provided with a wick having an extension, and a tank or reservoir to which said extension is extended and in which a portion of the same is confined, substantially as described. 70

17. In a device of the class specified, a moistening device provided with a wick having an extension, a portion of which is exposed, and a couple of tanks or reservoirs one arranged above the general level of the moistening device and adapted to supply liquid thereto and the other arranged below the moistening device, the said extension of the wick being extended to said second tank or reservoir, and a portion of the same confined therein, substantially as described. 80

18. In a device of the class specified, a moistening device comprising a box having openings in its sides for the entry and exit of the article to be moistened, and also having a wick inclosed by the walls and top of the box and located between said side openings. 90

19. In a device of the class specified, a moistening device comprising a box having openings in its sides for the entry and exit of the article to be moistened, and also having a wick inclosed by the walls and top of the box and located between said side openings, and means on the top of the box for pressing said article against the wick. 95

20. In a device of the class specified, a moistening device having an inclined section of wick adapted to receive liquid, and another portion of wick to be used for moistening purposes connected with the first-mentioned portion at the upper end thereof, whereby the surplus liquid will run away from the moistening portion. 100

21. In a device of the class specified, a moistening device having a lip 31^a.

22. In a device of the class specified, a moistening device comprising a box consisting of pieces 31, 32 and 33 whereof the piece 31 is provided with apertures 35, ribs 34, 34, and 37, and a tailpiece 38 and the piece 32 is constructed with a flange 42 and prongs 39, 40 and 41, and the piece 33 is constructed with ribs 43, 43 and a flange 44, screws 48 and 49 and a wick 45 extended between the prongs of the piece 32 and the ribs 43, 43, thence between the flange 42, and an overhang on the piece 31, and thence over the top of the latter, substantially as described. 115

In witness whereof we hereunto subscribe our names this 8th day of December, A. D. 1903.
